UNITED STATES PATENT OFFICE

127,569

DESIGN FOR A BURIAL VAULT HANDLE

Wilbert W. Haase, Forest Park, Ill., assignor to Wilbert W. Haase Co., Forest Park, Ill., a corporation of Illinois

Application November 20, 1940, Serial No. 96,710

Term of patent 14 years

To all whom it may concern:

Be it known that I, Wilbert W. Haase, a citizen of the United States of America, residing at Forest Park, in the county of Cook and State of Illinois, have invented, a new, original, and ornamental Design for a Burial Vault Handle, of which the following is a specification, reference being had to the accompanying drawing, forming a part thereof.

Referring to the drawing:

Figure 1 is an elevational view of a burial vault
handle embodying my new design.

Fig. 2 is a top view of Fig. 1; and,

Fig. 3 is an end elevational view.

I claim:

The ornamental design for a burial vault handle, as shown.

WILBERT W. HAASE.
